CLAIM

The ornamental design for a pedicure slipper, as shown and described.

DESCRIPTION

FIG. 1 is a perspective view of the pedicure slipper, showing my new design;

FIG. 2 is a top view thereof;

FIG. 3 is a left side view thereof;

FIG. 4 is a right side view thereof;

FIG. 5 is a front view thereof;

FIG. 6 is rear view thereof; and,

FIG. 7 is a bottom view thereof.

The broken lines represent the bottom of the slipper which forms no part of the invention.
